Application February 11, 1939, Serial No. 255,808
In Germany February 15, 1938

4 Claims. (Cl. 235—95)

This invention relates to an odometer for railway vehicles or the like, particularly to an odometer mounted in the axle box of the vehicle.

An object of the invention is to provide a simple and reliable construction for such odometers, permitting the accommodation of the odometer in different types of railway vehicles. An object, more particularly, is to allow mounting of the odometer in different axle boxes without requiring appreciable constructional changes of the axle boxes or the use of additional connecting pieces and box parts.

Another object of the invention is to prevent an incorrect registering due to unavoidable shocks of the vehicle axle occurring under severe operating conditions.

A further object of the invention is to render the indications of the odometer independent of displacements of the vehicle axle within the axle box. Such displacements occur in operation when displacing or adjusting the axle bearing in the case of worn-out axle brasses as well as when replacing the worn-out axle brasses by new ones.

A still further object of the invention is to ensure a long life of such odometers despite the severe shocks to which the axle boxes are subjected and to warrant at all times a proper lubrication of the individual parts of the odometer.

Further details of the invention will be apparent from the following description taken in connection with the accompanying drawings, in which

Figs. 1 to 3 show three different views of a preferred embodiment of the odometer according to the invention. Fig. 1 represents a side elevation, Fig. 2 a section along the dot-and-dash line 2—2 in Fig. 1, and Fig. 3 a front elevation of the odometer mechanism.

Figs. 4 to 8 show different views of odometers according to the invention mounted in axle boxes of different types. Figs. 4 and 5, in particular, illustrate a second embodiment, Fig. 4 showing a part-sectional side elevation of the complete odometer and Fig. 5 a front view with the cover of the odometer removed; Figs. 6 and 7 are part-sectional side and front elevations respectively of a third embodiment. Fig. 8 shows a part-sectional side view of another modification.

Referring at first to Figs. 1, 2 and 3, numeral 1 denotes a pocket-shaped supporting frame provided with suspension eyes 2. Two oscillatory arms 4 are pivoted on trunnions 3. A follower member consisting of a yoke 5 is linked by bolts

6 to the ends of the levers 4 so as to be capable of, and confined to, parallel motions in a direction transverse to the slot 40 of the yoke. The longitudinal sides of the slot 40 are bordered by two parallel ledges forming sliding surfaces 20.

A ratchet wheel 7 is mounted on a shaft 41 between the arms 4. The shaft 41 is journaled in the frame 1 and serves to actuate the counter of the odometer. The ratchet wheel 7 is advanced by a driving pawl 8 mounted on a cross-bar 10 which bridges the two arms 4. A retaining pawl or detent 9 also coacting with the wheel 7 prevents it from rotating in the opposite direction. A second shaft 42 also journaled in frame 10 is coupled with shaft 41 by means of gears 11 and 12 and carries a worm 13 driving a worm wheel 15. This worm wheel is firmly connected with the numeral wheel 14 for indicating the lowest digit (Fig. 3). The other numeral wheels 15 for indicating the higher digits are denoted by 16. They are coupled with wheel 14 by a tens transfer transmission as usual in such registering devices. Wheels 14, 15 and 16 are mounted on a common axle 43 in an extension 17 of the supporting frame 1 and are covered by a guard 19 provided with windows 18.

The planes of the sliding surfaces 20 extend vertically and in the direction of the vehicle axle 21 (see Fig. 4). A driver 24 composed of rawhide disks 25 is secured eccentrically to the end surface 22 of the axle 21 by means of a flange 23 (Fig. 4). The sliding surface of the driver is completely cylindrical and its axis is parallel to that of axle 21. When the axle 21 revolves, the driver 24 causes the yoke 5 and the arms 4 to oscillate and to actuate the ratchet and gear transmission driving the registering device. Due to the particular arrangement of the coacting sliding surfaces of the driver and the yoke, the unavoidable vertical strokes of the vehicle axle are prevented from damaging the odometer device or affecting its proper operation. It is of essential advantage with respect to this protective function that the bolt 6 connecting the yoke 5 with the arms 4 be arranged in or near the horizontal axial plane of the axle 21, i. e. within the vertical zone of the kinematic engagement between the pin 24 and the slide surfaces 20, and it is also preferable to arrange the points of attachment of the frame 1, i. e. the eyes 2, also within the just-mentioned vertical zone. This design renders vertical strokes virtually ineffective and, besides, results in a relatively simple and space-saving construction. Due to the same arrangement, in particular of the slid-

ing surfaces, an axial displacement of the axle or of its bearing is also without disturbing effect.

The arrangement shown in Figs. 4 and 5 is similar to that above-described, except that the bearing 44 of the vehicle axle 21 is provided with an oil trough 28 separate from the axle box, the latter consisting of a casing 26b and a cover 26c.

In the embodiment according to Figs. 6 and 7, the odometer is fastened to two angle pieces 39 secured to the axle box 31. In this case the device is arranged in a separate sheet metal trough 32 which collects a portion of the lubricant poured into the bearing through the aperture 33.

According to Fig. 8 the odometer is arranged within a hood 36 which covers the opening 34 of the bearing cover 35. The aperture 37 permits the reading of the register. 32 denotes a sheet iron trough which retains the lubricant for the odometer.

What is claimed is:

1. An odometer to be actuated by a wheel axle of a vehicle, in particular for railway vehicles, comprising a driving member mounted eccentrically on an end face of said vehicle axle, a movable member arranged in front of said end face in direct and constrained engagement with said driving member as regards the horizontal component of the motion of said driving member, said movable member being designed to allow said driving member free relative movements in the vertical and axial directions, a supporting structure to be secured to said vehicle, a parallelogram mechanism comprising two arms movably arranged and spaced from each other in the plane of movement of said movable member, said arms having one end pivotally secured to said structure and spaced in the vertical direction from said axle, the other ends respectively of said arms being linked to said movable member at places within the vertical range of movement of said driving member, a counting device having rotary counter members, and transmission means operatively connecting said mechanism with said device for transforming the oscillatory motion of said mechanism into a unidirectional rotation of said counting members.

2. An odometer to be actuated by a wheel axle of a vehicle, in particular for railway vehicles, comprising a driving pin mounted on an end face of said axle so as to have its geometrical axis in parallel to that of said axle, a yoke member arranged substantially in a vertical plane in front of said end face, said yoke having a vertical slide surface engaging said driving pin so as to allow relative axial displacements between said yoke member and said pin, a parallel motion guiding mechanism for confining said member to oscillatory parallel displacements along said vertical

plane, said mechanism being linked to said yoke member at places within the vertical range of movement of said pin, a counting device having rotary counter members, and transmission means operatively connecting said mechanism with said device for transforming the oscillatory motion of said mechanism into a unidirectional rotation of said counting members.

3. An odometer in combination with a bearing 10 of a wheel axle of a vehicle, in particular a railway vehicle, comprising a frame structure connected with said bearing, a driving pin eccentrically mounted on an end face of said axle, a movable follower member having an elongate 15 slot and arranged in front of said end face in engagement with said pin so as to exert substantially horizontal oscillations due to rotations of said pin while allowing free relative vertical and axial movements of said pin, a parallel-motion 20 mechanism for guiding said follower member, said mechanism being linked with said member at points within the vertical zone of the operating range of said engagement, a counting device having rotary counter members, and transmission means 25 operatively connecting said mechanism with said device for transforming the oscillatory motion of said mechanism into a unidirectional rotation of said counting members, said guiding mechanism, said counting device, and said transmission means being mounted on said frame structure.

4. In combination with an oil container associated with a bearing of an axle of a railway vehicle, an odometer comprising a supporting frame 30 firmly attached to said oil container, said frame having its points of attachment arranged near said axle and containing a bottom portion suspending below said axle, a driving pin eccentrically mounted on the end face of said axle, a yoke arranged in front of said end face and having a vertical slot bordered by opposite sliding surfaces engaging said pin, two parallel guiding arms arranged in substantially vertical direction and in parallel relation to each other, said arms 35 having their lower ends pivotally mounted on said bottom portion of said frame and their upper ends linked to said yoke substantially in the horizontal axial plane of said axle and forming part of a parallelogram mechanism for confining said yoke to parallel motions, a ratchet gear having a ratchet wheel rotatably mounted on said bottom portion of said frame, and a driving pawl connected with said mechanism in order to transform the oscillatory motion of said mechanism 40 into a unidirectional rotary motion, and a counter mounted on said frame and operatively connected with said ratchet wheel.
